UNITED STATES PATENT OFFICE.

CALEB C. PIERSON, OF ELIZABETH, NEW JERSEY.

TRUSS-FRAME FOR LADDERS.

SPECIFICATION forming part of Letters Patent No. 392,361, dated November 6, 1888.

Application filed March 31, 1888. Serial No. 269,109. (No model.)

To all whom it may concern:

Be it known that I, CALEB C. PIERSON, of Elizabeth, in the county of Union and State of New Jersey, have invented a new and Improved 5 Truss-Frame for Ladders, of which the following is a full, clear, and exact description.

My invention consists, principally, of a truss-frame to be applied to ladders, whereby the same may be conveniently and safely used for 10 a scaffold.

The invention also consists of the construction, arrangement, and combination of parts, all as hereinafter described and claimed.

Reference is to be had to the accompanying 15 drawings, forming a part of this specification, in which similar letters of reference indicate corresponding parts in all the figures.

Figure 1 is a perspective view of my invention applied to a ladder, the same being shown 20 as upheld from ropes by means of triangles. Fig. 2 is an enlarged transverse sectional elevation on the line $x-x$, Fig. 1; and Fig. 3 is an enlarged perspective view of one end of one of the lower cross-bars of one of the truss-frames.

25 A represents a ladder, shown in position for use as a scaffold, being supported from the ropes R R by the triangles B B.

C are truss frames applied to the under 30 side of the ladder. These frames are duplicates of each other, each being composed of two uprights, $a a$, lower cross-bar, b , intermediate cross-bars, $c c$, and side braces, $d d$. The upper ends of the uprights $a a$ are notched 35 at $a' a'$ to fit upon the rung of the ladder, as shown clearly in Fig. 2. The cross-bar b is longer than the width of the ladder, and is provided at each end with a roller, e , adapted to run in contact with the side of the house to swing the ladder away from contact with the 40 house.

D are iron rods formed with hooks d and connected to the center of the cross-bar b by an eyebolt, d' , upon the outer screw-threaded end of which is placed a nut, d'' , by which the

rods may be drawn downward after being 45 hooked upon the rungs of the ladder, as illustrated in Fig. 1, to firmly lock the truss-frames in contact with the rungs of the ladder.

The ladder is stiffened by the two ropes E E, attached at each end by hooks $f f$ to the rungs 50 of the ladder and passed through the openings or slots $g g$ at the ends of the cross-bars b , as shown clearly in the drawings.

When the truss-frames and the ropes E are applied to the ladder as shown, the same is 55 made very stiff, so that it can be safely and conveniently used as a scaffold, and the said frames and ropes may be very quickly and easily applied and as easily detached.

Having thus described my invention, what I 60 claim as new, and desire to secure by Letters Patent, is—

1. The frame C, formed with the uprights a , suitably held together and braced, and the cross-bar b , projecting beyond the uprights a , 65 in combination with the rods D, adjustably attached to the center of the cross-bar b , substantially as described.

2. The uprights $a a$, notched to engage with the rung of a ladder, the rods D D, and cross-bar b , projecting past the said uprights and provided with the rollers e , substantially as 70 described.

3. The uprights $a a$, notched to engage with the rungs of the ladder, the rods D D, and the 75 cross-bar b , notched at g to receive the ropes E, substantially as described.

4. The two frames C, applied to the ladder and held by the rods D D, in combination with the ropes E E, attached at their ends to the 80 rungs of the ladder and connected to the ends of the cross-bars $b b$ of frame C, substantially as described.

CALEB C. PIERSON.

Witnesses:

H. A. WEST,
C. SEDGWICK.
